US0D1034066S

(12) **United States Design Patent** (10) **Patent No.:** **US D1,034,066 S**
(45) **Date of Patent:** **** Jul. 9, 2024**

(54) **CONTAINER FOR AIR FRYER**

(71) Applicant: **Juan Deng**, Zhuzhou (CN)

(72) Inventor: **Juan Deng**, Zhuzhou (CN)

(*) Notice: Patent file contains an affidavit/declaration under 37 CFR 1.130(b).

(**) Term: **15 Years**

(21) Appl. No.: **35/514,887**

(22) Filed: **Jul. 18, 2022**

(80) **Hague Agreement Data**

Int. Filing Date: **Jul. 18, 2022**

Int. Reg. No.: **DM/222437**

Int. Reg. Date: **Jul. 18, 2022**

Int. Reg. Pub. Date: **Aug. 12, 2022**

CLAIM

The ornamental design for a container for air fryer, as shown and described.

DESCRIPTION

1.1 is a top perspective view of a container for air fryer showing my new design;

1.2 is a bottom perspective view thereof;

1.3 is a front view thereof;

1.4 is a rear view thereof;

1.5 is a left view thereof;

1.6 is a top view thereof; and

(Continued)

1.7 is a bottom view thereof.

1 Claim, 7 Drawing Sheets
